ELECTRIC SWITCH

Martin F. Koenig, Milwaukee, Wis., assignor to
 Cutler-Hammer, Inc., Milwaukee, Wis., a corporation of Delaware

Application January 3, 1950, Serial No. 136,570

5 Claims. (Cl. 200—153)

1

This invention relates to electric switches and more particularly to rotary switches of the slow-make, slow-break type adapted to control relatively high capacity alternating current circuits.

A primary object of the invention is to provide a smaller, more compact, and more rugged switch of the aforementioned character which will have higher current carrying capacity for its size than switches heretofore known.

Another and more specific object of the invention is to provide in a switch of the aforementioned character novel contactor construction which affords a switch of smaller size and higher current carrying capacity.

A further object of the invention is to insure positive contact pressure in a switch of the type under consideration when the switch is in a circuit-making position.

Another object is to provide a switch affording a multiplicity of different circuit controlling characteristics by the addition, substitution, and/or rearrangement of a minimum number of parts.

Another object is to provide a switch of the aforementioned character of simplified construction and consisting of a relatively small number of parts which are easier to assemble and less expensive to manufacture than prior switches of comparable current controlling capacity.

Other objects and advantages will hereinafter appear.

The accompanying drawings illustrate certain preferred embodiments of the invention, it being understood that the embodiments illustrated are susceptible of modification within the scope of the appended claims.

In the drawings, Figure 1 is a side elevational view of a single wafer multiple circuit controlling form of the switch adapted for "one-hole" mounting;

Fig. 2 is a sectional view taken on the broken line 2—2 of Fig. 1;

Fig. 3 is a sectional view taken on the line 3—3 of Fig. 1;

Fig. 4 is a sectional view taken on the line 4—4 of Fig. 1 and illustrating the switch with all of its parts in open-circuit position;

Fig. 5 is a view similar to that of Fig. 4 but illustrating certain of the switch parts in circuit-making position;

Fig. 6 is an end elevational view of a switch embodying the invention and illustrates the addition of a second wafer unit as well as superstructure affording flush mounting of the switch, and

2

Fig. 7 is a sectional view taken on the line 7—7 of Fig. 6.

Referring to the drawings, the reference numeral 10 designates an extremely shallow recessed base of contour best illustrated in Figs. 4, 5 and 7 molded from a suitable insulating material, such as "Bakelite." As will be apparent, the switch may comprise one or more of such bases or wafer units depending upon the circuit 10 controlling characteristics desired. Mounted at each side of a recess 10^a of base 10 in such a manner as to permit access thereto from the exterior of the base 10 through windows or openings 10^b, are combined stationary contact and 15 terminal members 11 comprising a contact portion 11^a, a flat connecting conductor portion 11^b and a terminal portion preferably comprising a binding screw 11^c. As shown in Fig. 4, provision is made for mounting one of such members 11 at 20 each side of recess 10^a, if desired. However, if only one of such members is required, an insulating closure 12^a (Fig. 7) may be utilized to plug each unused window to aid in rendering the switch dust tight.

25 The switch is further provided with contactors 13 to cooperate with each of the stationary contacts 11, said contactors being of resilient current conducting material and being of the form best illustrated in Figs. 4, 5 and 7. Each of such 30 contactors 13 comprises a contact portion 13^a, a terminal portion 13^b preferably carrying a binding screw assembly 14, and a flat double reflexed connecting portion 13^c of S-shape as illustrated. Each of the contactors or movable contact carriers 13 is mounted within recess 10^a of base 10 at 35 one or the other sides thereof with their respective contact portions 13^a in position to make contact with the contact portion 11^a of their respective cooperating stationary contacts as shown; while the terminal portion 13^b of each contactor projects beyond the side wall of recess 10^a through a slit 10^c therein and into an auxiliary recess 10^d, said slit and the walls of 40 said recess 10^d being adapted to maintain contactor 13 in position and said auxiliary recess being adapted to accommodate the aforementioned binding screw assembly 14. As shown said auxiliary recess 10^d opens to the exterior of base 10 to render the binding screws accessible therefrom. Where any of the recesses 10^d are not utilized, they may be plugged with insulating members 12^b (Fig. 7).

45 Contactors 13 being of resilient material, are formed so that contact portions 13^a are biased 50 away from their respective cooperating stationary 55 members 11.

contacts 11, engagement thereof being effected by positive action of a cam member 15 rotatably mounted within recess 10^a of base 10 (Figs. 4 and 5) preferably centrally thereof. The cam 15 may be of the contour illustrated therein or may be of any other desired contour, as for example, the contour of the cam 15 illustrated in Fig. 7, to effect any desired commutation of contactors 13 and stationary contacts 11.

Rotation of cam 15 is effected by rotation of a shaft 16 (Fig. 2) which may be of sufficient length to extend through all of the wafer units utilized and preferably has a portion 16^a of polygonal form in cross section to effect non-rotatable connection with each cam 15 utilized. As illustrated, the aforementioned portion 16^a is square in cross section whereas the openings 15^a in cams 15 are of star shape to afford connection therebetween in various angular relationships.

As will be apparent, rotation of cam 15 will effect movement of contactors 13 from their biased open position as shown in Fig. 4 to the circuit-making position illustrated by the right hand contactor 13 in Fig. 5, such movement being effected by a camming action against the inherent bias of contactors 13 to effect engagement of the contacts and ultimately to compress the double reflexed portions 13^b in accordion fashion thereby absorbing the remaining movements of cam 15 in reaching circuit-making position. The aforementioned compression of contactors 13 after engagement of the contacts 13^a and 11^a not only insures positive and constant contact pressure in the closed position of the switch contacts but also the concomitant accordion like movements of contactors 13 lessens the strain and prolongs the life of the contactors. Moreover, the aforescribed arrangement, construction, and cooperation of parts not only provides a switch of fewer and simpler parts and of more rugged construction, but affords higher current controlling capacity while maintaining a minimum size for the switch.

As aforementioned, switches embodying the invention may be constructed of one or more wafer units stacked one above the other with insulating members 17 interposed therebetween, each unit being of similar construction and having a common actuating shaft 16 extending therethrough. Additionally, the switch units have a common superstructure which may be of construction similar to that disclosed and more fully described in Patent No. 2,395,572 issued to Meuer et al. and assigned to the same assignee as is the present invention. As will be understood, such superstructure may comprise a cover plate 18, indexing and positioning means 19 (Fig. 2) and a pair of cooperating stop plates 20^a, 20^b (Fig. 3) to limit rotation of shaft 16 if desired. Additionally, the switch may be provided with "one-hole" mounting means 21 (Fig. 2) comprising an externally threaded bushing 21^a and associated nuts 21^b, or means for flush mounting (Fig. 6) comprising a superstructure 22 attached to cover plate 18 preferably by means of rivets 23 which extend through each of the wafer units utilized and maintain the entire switch in assembled relation.

As best illustrated in Figs. 4 and 5, further circuit controlling characteristics may be provided in the switch by the addition of connecting busses 24 bridging binding screws 14 of the same wafer unit, and similar connecting busses 25 (Fig. 7) may be utilized to vertically connect binding screws 14 or 11^c of adjacent wafer units where more than one of the latter is utilized, thus

affording a switch having a great variety of circuit controlling as well as circuit commutating characteristics by addition and/or arrangement of a very few simple parts.

5 I claim:

1. In a compact slow-make, slow-break rotary switch capable of handling relatively high capacity alternating current circuits, a stationary contact, a contactor inherently biased out of engagement with said stationary contact and comprising a flat resilient conducting member of double reflexed form, and a rotatable cam to initially move said contactor against its inherent bias into engagement with its cooperating stationary contact and with further rotation compress said contactor in accordion fashion to maintain positive and constant pressure between the engaged contacts.

2. In a compact slow-make, slow-break rotary

switch capable of handling relatively high capacity alternating current circuits, a stationary contact, a cooperating movable contact, and means for effecting engagement of said contacts and to insure positive and constant contact pressure during such engagement, said means comprising a strip type resilient contact carrier having at least two reflex bends and carrying said movable contact, said contact carrier inherently biasing said movable contact out of engagement with its cooperating stationary contact, and means for effecting movement of said contact carrier against its inherent bias to effect engagement of said contacts and with further movement compress the double reflexed bends of said contactor in accordion fashion to maintain positive and constant pressure between the engaged contacts.

3. In a compact slow-make, slow-break rotary switch, a stationary contact, a contactor inherently biased out of engagement with said stationary contact and comprising a flat resilient conducting member having at least two reflex bends, and a rotatable cam to effect movement of said contactor into engagement with its cooperating stationary contact, remaining movement of said cam to its full circuit-making position compressing the double reflexed bends of said contactor in accordion fashion to afford positive and constant contact pressure between said contactor and its cooperating stationary contact.

4. In a compact A. C. rotary electric switch, the combination with an insulating base having a recess for housing the switch parts, of a combined stationary contact and terminal member mounted in said recess and having a terminal portion accessible exteriorly of said base, a movable contact, a resilient contactor having a terminal portion anchored to said base and accessible exteriorly thereof, said contactor also having a free end carrying said movable contact and having a double reflexed intermediate portion inherently biasing said movable contact out of engagement with its cooperating stationary contact, and means engageable with the free end of said contactor for movement of said movable contact into engagement with its cooperating stationary contact as a stop and thereafter compressing said reflexed intermediate portion in accordion fashion to maintain positive and constant pressure between said contacts.

5. An A. C. rotary electric switch comprising in combination, at least one wafer type switch unit comprising an insulating switch housing, a stationary contact within said housing, a movable contact for cooperation with said stationary contact, a resilient contactor within said housing

having one end anchored thereto and also having a free end carrying said movable contact and a double reflexed intermediate portion inherently biasing said movable contact out of engagement with said stationary contact, means engageable 5 with the free end of said contactor for movement of said movable contact into engagement with its stationary contact as a stop and thereafter compressing said reflexed intermediate portion in accordian fashion to maintain positive and constant pressure between said contacts, switch operating means connected to said last mentioned means, and means affording attachment at will of other similar wafer type switch units including connections affording operation of such additional wafer units by said aforementioned switch operating means. 15
